UNITED STATES PATENT OFFICE.

JOSEPHINE G. ROVIRA, OF NEW YORK, N. Y.

COMBINATION CATAMENIAL DRAWERS.

1,112,162.

Specification of Letters Patent.

Patented Sept. 29, 1914.

Application filed April 18, 1912. Serial No. 691,587.

To all whom it may concern:

Be it known that I, JOSEPHINE GUILLEMARCHAND ROVIRA, a citizen of Republic of France, and a resident of the borough of Manhattan, county, city, and State of New York, have invented certain new and useful Improvements in Combination Catamenial Drawers, set forth in the following specification.

10 This invention relates to women's wearing apparel and particularly to sanitary catamenial drawers.

An object of the invention is to combine, with a pair of drawers, a catamenial-pad supporting belt and a waterproof lining for the drawers, and to so arrange and connect the parts that they may be readily disconnected one from the other to the end that the drawers and belt may be used without the 20 lining, the drawers and lining without the belt, or any other desired combination made.

A further object is to shape the body portion of the drawers substantially flat and adapted to be brought forward about the 25 body of the wearer and fastened at the front but leaving an opening at the bottom, and to form said body portion with a flap, continuing from the seat of said drawers, for closing said opening, and to form said flap so 30 as to comprise angularly disposed portions adapted to extend obliquely downwardly to lend appropriate form to the inner sides of the legs of the drawers without producing undue fullness in the crotch.

35 A further object is to form said waterproof lining with suitable fullness so as to lie smoothly over the seat and crotch and into the leg portions of the drawers.

A further object is to form the pad supporting belt so that the same may be readily adjustable without removing the front pad attaching tab thereof from a substantially central position. And a still further object is to provide a novel and improved means of 45 connection between the opposite ends of the pad and the front and rear tabs of the belt.

These and further objects are set forth in the following claims which should be read in connection with this specification which 50 has reference to illustrative embodiments of the invention, shown in the accompanying drawings, which form a part of this application, and in which,—

Figure 1 is a front elevational view of 55 the improved drawers; Fig. 2 is a transverse vertical sectional view taken substantially on

the plane of line II—II of Fig. 1; Fig. 3 is a front elevational view of the drawers spread open. Fig. 4 is an enlarged detail view of one of the pad attaching tabs of the 60 pad supporting belt; Fig. 5 is a diagrammatic transverse sectional view taken vertically through the rear portion of the belt and adjacent portions of the drawers and waterproof lining, and illustrating graphically the arrangement of the connections between said parts; and Fig. 6 is a view similar to Fig. 5, but illustrating a modified arrangement of the connecting means between the belt, drawers, and lining. 70

Referring to the drawings by numerals, 1 indicates the body portion of the drawers which may comprise any number of suitably shaped sections connected by seams 2, all combining to form a suitably shaped, substantially flat, body portion adapted to extend about the body of the wearer and to have opposite end portions 3 lap each other and be fastened together at the front by fastening means such as the vertical row of 80 buttons 4 and button-holes 5 shown.

When the portions 3 are connected, the otherwise open space therebelow is closed by a flap 6 which continues from the seat portion of the drawers and which is adapted to 85 be folded upwardly to lap and be connected to the angularly disposed edge portions 7 of the body of the drawers as by the buttons 8 and button-holes 9. The legs of the 90 drawers are thus divided lengthwise of the front and portions of said legs form parts of the flap 6 which may be readily opened when desired. The central button-hole 9 engages the lowest button 4.

The suitably shaped waterproof lining 10 95 is removably attached to the inner surface of the drawers, in position for covering the seat and crotch, by having its rear end detachably engaging the drawers at or near the waist band, by having its central or seat portion 100 detachably connected to the drawers as by the tabs 11 with their snap connections 12, and by having its front end detachably connected to the flap 6 by the part 13 with its snap connections 14. 105

In order that the lining 10 may have a desirable shape at the crotch for disposing its opposite side portions so as to extend obliquely downwardly into the legs for avoiding unnecessary fullness at the crotch, 110 said lining is slit from its front edge 15 rearwardly toward the seat. The portions

17 at opposite sides of said slit are then spread so that the parts of the front edge at opposite sides of said slit are in angular relation to each other, the degree of angularity coinciding substantially with the degree of the angle formed by the edge portions 7 when the drawers are closed. A gusset 18 is then fitted into the space between said spread portions, the outer edge 10 contour of the gusset being preferably such as to continue the lines of the now angularly disposed portions of the edge and the whole is stitched and suitably bound. In this simple manner ample fullness as at 19 is provided at the appropriate localities.

The flap 6 of the drawers is slit and fitted with a gusset 20 in precisely the same manner as described for the lining, and the spread portions 21 of said flap assume an 20 angular relation to each other which lends desirable shape to the inner sides of the legs without fullness at the crotch. The fullness 19 of the lining is thus accommodated and both lining and drawers lie substantially smooth over the crotch and seat.

The belt 22 is formed with an independently formed front section 23. A catamenial attaching tab 24 depends from the belt 22 at the rear and a similar tab 25 depends from 30 the belt front section 23. The belt front section is adjustably connected with each of the ends of the belt proper 22, as by the buttons and button-holes 26, so that the belt may be readily adjusted in length without 35 the necessity of removing the tab 25 from a desirable central position.

Preferably each of the tabs 24 and 25 is formed with a longitudinally extending slot 27 and each of said slots is bridged at intervals by suitable retainers 28 forming means for adjustably securing the catamenial pad to the said tabs. In the embodiment illustrated these retainers are shown as V-shaped members formed preferably of stiff wire and 45 having eyes 29 by means of which they are attached to the tab at opposite sides of the slot.

In use the opposite ends of the pad 30 are formed with large knots 31 and these 50 knots are passed through the slots 27 above the desired retainers 28 and, when lowered, engage said retainers, and are positively supported thereby.

In the structure shown in Figs. 1, 2, 3, 55 and 5 the rear end of the lining 10 is supported directly from the belt 22 as by the buttons and button-holes or other suitable detachable connecting means 32, and the belt is in turn fixed to the drawers by 60 the buttons and button-holes or other suitable detachable connecting means 33. As shown in these figures the belt is formed with button-holes to receive the buttons fixed

to the lining and the drawers are formed with button-holes to receive buttons fixed 65 to the belt. In Fig. 6 the precise arrangement of the buttons and button-holes is altered. The lining is here formed with button-holes to receive buttons 34 on the belt, and the belt is formed with button-holes to 70 receive buttons 35 on the drawers. This modified arrangement more readily accommodates itself to various combinations of any two of the parts—drawers, lining, or belt—with the third.

75

What is claimed and what is desired to be secured by United States Letters Patent is:—

1. In a sanitary catamenial garment, the combination with a pair of drawers of a 80 catamenial-pad-supporting belt connected to said drawers; and a water-proof lining for said drawers connected to said belt.

2. In a sanitary catamenial garment, the combination with a pair of drawers, of a 85 catamenial-pad-supporting belt detachably connected to said drawers at the back thereof; and a waterproof lining for said drawers detachably connected at its rear end to said belt and being detachably connected 90 at its front end to the front portion of said drawers.

3. In a sanitary catamenial garment, the combination with a pair of drawers, of a 95 catamenial-pad-supporting belt connected to said drawers; and a waterproof lining for said drawers detachably connected to said belt and being detachably connected to parts of said drawers.

4. In a sanitary catamenial garment, the 100 combination with a pair of drawers, of a catamenial-pad-supporting belt; belt attaching means for detachably connecting said belt to said drawers; a waterproof lining for said drawers; and means for interchangeable connecting said waterproof lining either to said belt or to said belt-attaching means.

5. A catamenial-pad supporting belt 110 formed with a pendent catamenial-pad attaching tab at its rear; and an independently formed belt front section having a pendent catamenial-pad attaching tab formed thereon, one of said catamenial-pad attaching tabs being formed with a longitudinally extending slit; and means bridging said slit at intervals comprising means for adjustably securing a catamenial pad to said tab.

In witness whereof, I have signed my 120 name to this specification, in the presence of two subscribing witnesses.

JOSEPHINE G. ROVIRA.
